M. P. HOLMES

REEL

Filed Nov. 20, 1916

Patented May 1, 1923.

1,454,017

UNITED STATES PATENT OFFICE.

MORRIS P. HOLMES, OF CLAREMONT, NEW HAMPSHIRE, ASSIGNEE, BY MESNE ASSIGNMENTS, TO THE JEFFERY MANUFACTURING COMPANY, OF COLUMBUS, OHIO, A CORPORATION OF OHIO.

REEL.

Application filed November 20, 1916. Serial No. 132,451.

To all whom it may concern:

Be it known that I, MORRIS P. HOLMES, a citizen of the United States, residing at Claremont, in the county of Sullivan and 5 State of New Hampshire, have invented certain new and useful Improvements in Reels, of which the following is a full, clear, and exact specification.

My invention relates to reels.

10 It has for its object to provide an improved reel adapted to wind up or unreel an electric conductor or the like, and especially adapted to use in connection with mining machines, wherein as the machine is moved 15 about the mine it is desirable for the electrical conductor or other means of supplying motive power thereto to be wound up and unwound as the machine proceeds about the mine. A more specific object of my invention 20 is to provide an improved and simplified construction having great flexibility and adapted to use under varying conditions. Other objects and advantages of my invention will, however, hereinafter more fully 25 appear.

In the accompanying drawings, I have, for purposes of illustration, shown one embodiment which my invention may assume in practice, illustrating the same as applied to 30 an electric conductor reel adapted to use in connection with a mining machine.

In these drawings,—

Fig. 1 is a side elevation of the reel.

Fig. 2 is a plan view of the same.

35 Fig. 3 is a transverse view partially in section, taken on line 3—3 of Fig. 1, the reel being shown as disconnected from its driving mechanism.

Fig. 4 is a partial longitudinal sectional view taken on line 4—4 of Fig. 3.

40 Fig. 5 is a transverse sectional view taken on line 5—5 of Fig. 3.

Fig. 6 is a transverse view partially in section taken on line 6—6 of Fig. 3.

45 In the illustrative construction, I have shown a trailer reel frame comprising side members 1 and 2 having converging forwardly extending ends rigidly connected at 3, and pivotally connected at 4 to a clevis 5 preferably suitably bushed and adapted to be 50 pivotally connected, as on a vertical pivot, at 6 to the mining or other leading machine 7. As shown, these side members 1 and 2 are connected by front and rear brace members 8 and 9 in such a manner as to form a rigid 55 frame.

Disposed between the lower edges of these members 1 and 2 and carried thereby, are parallel transverse members 10. As shown, these members 10 are tubular and seated in lower inwardly projecting sleeves 11 and 12 60 formed on separate frame members or castings 2^a and 1^a carried on the outside of the members 2 and 1. Slidably mounted in each of these tubular members 10, is an axle or shaft 13, which is preferably removable 65 through a suitable bore 14 registering with the sleeve 12. As shown, each of these shafts 13 is fixed in position within its tubular member 10 by means of a suitable setscrew 15. Journaled upon the outer ends of these 70 shafts, and outside suitable spacing rings 16, are small track wheels 17 preferably of the same size. As shown, each of these wheels 17 is held in position on the shaft by a combined cap and oil cup 18 fixed to the shaft 75 by a suitable pin 19 and having an oil passage 20 therein communicating with a longitudinally and laterally extending oil passage 21 in the end of the shaft, which acts to supply lubricant to the surface of the shaft 80 on which the wheel 17 is journaled.

Cooperating with these wheels and on the opposite side of the frame therefrom, is a larger wheel 22 which is journaled on a laterally disposed sleeve 23 formed on the frame member 2^a, the wheel 22 being held 85 in position thereon by a suitable pin 24 and a washer 25. Within this wheel 22 and journaled on the hub of the wheel 22, is carried a gear 26 having a laterally extending sleeve 27 thereon, and a flange 28 disposed adjacent the outer face of the wheel 22. Cooperating 90 with this flange and acting to connect the same to or disconnect the same from the wheel, is another plate 29, preferably disposed parallel thereto and having a series of radially disposed nut-locking sockets 30 formed therein, in which are carried bolts 31, nuts 32, and springs 33, the bolts extending through the wheel 22 at a plurality 95 of points adjacent its periphery, and having heads 34 thereon by rotation of which the tension of the springs may be adjusted from the exterior of the wheel. Thus, it will be noted that the gear 26 may be connected to or disconnected from the wheel 22, as desired, through the frictional clamping 100 means described, and that the latter may be set to slip at any desired point.

Cooperating with the gear 26 and meshing therewith, is a pinion 35, preferably dis- 110

posed above the same and journaled in a suitable bearing on the upper part of the frame member 2^a, the pinion preferably having a flanged sleeve 36 thereon extending through the frame member and holding the pinion in position thereon, and a removable bearing sleeve 37 preferably being provided between the frame member and this sleeve. Within the sleeve 36 is slidably received a reel shaft 38, the latter being provided with a squared end 39 adapted to be received in a correspondingly shaped portion 40 within the sleeve, so that when the shaft 38 is moved into engagement with that portion, the reel shaft will rotate with the pinion 35. The opposite end of this shaft 38 is, as shown, also preferably journaled in a suitable bearing sleeve 41 carried in an outer revoluble sleeve member 42. This sleeve 42 is in turn mounted upon the frame member 1^a and provided with a plurality of spaced radially disposed lugs 43 thereon, one of which is adapted to register with and move longitudinally through a slot 44 in the frame member to the position shown in Fig. 3, the lugs upon rotation of the sleeve, locking the same against withdrawal (Fig. 5), or, when reversely operated, permitting the withdrawal of the same. As shown, the shaft 38 is also provided with a squared end 45, whereby the same may be rotated in any position of the sleeve 42 by the use of a suitable handle, if desired. It will also be noted that a suitable collar 46 is pinned to the shaft 38 outside of the member 42, while a corresponding collar 47 is pinned to the shaft at a point inside the sleeve 41. Thus, the shaft 38 may be reciprocated with the sleeve 42.

40 In the form of my invention illustrated, the sleeve 41 is provided with upstanding arms or projections 48 thereon, extending on opposite sides of a pin or stud 49 on a stationary contact carrying element 50.

45 As shown, this pin 49 is reciprocable in the socket formed by these arms, and is normally held in position therein by a removable cover 51 carried on the upper part of the frame 1^a. As illustrated, the member 50 is also preferably connected through a suitable connector receiving member 52 to a conductor A leading to the machine 7, and is provided with suitable contact members 53 adapted to receive current from cooperating rotary contacts 54 carried on the ends of a conductor reel 55, fixed to and rotatable with the shaft 38. Thus, by connecting one end of a conductor wound on the reel 55, to these contacts 54, current may be supplied to the machine as the latter moves about the mine. As illustrated, a similar stud 56 is also provided on a similar contact-carrying member 57 disposed at the opposite end of the reel 55. This member 57 also carries contacts 58 engaging other rotary reel contacts

59, and is likewise connected through a similar connector 60 to a conductor B leading to the machine. As shown, it also has a pin or stud 56 adapted to move into a suitable socket 61 formed in the upper part of the other frame member 2^a. Between the contacts 54 and 59, the conductor 62 is, of course, connected and wound around the reel in the usual manner, one end of the same being extended to the line. Obviously, during the normal operation of the device, it is also desirable to attach the reel securely to the truck, and for this purpose attaching means 63 are disposed over the recess 61 and the stud, which are removable to permit that end of the reel to be removed bodily if desired.

In the use of my improved reel, it will be noted that the reel 55 will normally be revolved through the rotation of the wheel 22, the contact carrying elements 50 and 57 remaining stationary while the reel is rotated to wind up or unreel a cable carried thereon. Attention is also directed to the fact that through the frictional connection between the wheel 22 and the reel 55, slippage may occur at any desired tension, as the point at which this slippage occurs may be regulated as desired by manipulation of the bolt heads 34 adjustable from the exterior of the wheel 22. Obviously, through the provision of the means for connecting or disconnecting the reel shaft 38 and the pinion 35, the reel 55, when in its normal position, may also be disconnected from the wheel 22 whenever desired by simply withdrawing its shaft 38 to the position shown in Fig. 3, and the reel may be again connected for rotation by the wheel, by simply moving the shaft bodily to the right from the position shown in that figure, the reel being locked in position by movement of the sleeve 42. If desired, it will also be noted that, the reel 55 may be rotated by hand by simply connecting a suitable crank to the squared free end 45 thereof. It will also be evident that by reason of the telescopic axles or shafts 13 and the setscrews 15 therefor, the wheels 17 may also be adjusted to adapt the device to use on tracks of different gauge, by simply releasing the setscrews, adjusting the shafts to the desired degree, and readjusting the setscrews. Attention is also directed to the fact that by the provision of the small wheels at one side of the truck, access is readily had to the reel, and that the latter may be readily removed from the truck when desired by lifting out the same over the small wheels after the attaching means 51 are removed. These and other advantages of my improved construction will, however, be clearly apparent to those skilled in the art.

While I have, in this application, specifically described one embodiment which my

invention may assume in practice, it is to be understood that the form shown herein is used for illustrative purposes, and that the invention may be modified without departing from its spirit, it being my intention to include all such modifications within the scope of the appended claims.

What I claim as new and desire to secure by Letters Patent is:—

10. 1. In a reel transporting means, wheeled reel supporting axles disposed in different horizontal planes, a reel, and means for supporting said reel for rotation about an axis spaced from said first mentioned axes and whereby said reel intersects one of said planes. 70
15. 2. In a reel transporting means, wheeled axles disposed in different planes, reel supporting wheels of different diameters on said axles, a reel, and means for supporting said reel for rotation about an axis spaced from said first mentioned axes and in a position to intersect one of said planes. 80
20. 3. In a transporting means, longitudinally spaced wheeled reel supporting axles disposed in different horizontal planes, a reel rotatable about an axis spaced from the axes of said axles, and means for supporting said reel so that it intersects one of said planes. 85
25. 4. In a reel transporting means, spaced axles disposed in different horizontal planes, reel supporting wheels of different diameters on said axles, a reel, and means for supporting said reel for rotation about an axis spaced from said first mentioned axes and in a position to intersect one of said planes. 90
30. 5. In a reel transporting means, axles disposed in different planes, reel supporting wheels of different diameters on said axles, a reel, means for supporting said reel for rotation about an axis spaced from said first mentioned axis and in a position to intersect one of said planes, and means driven by one of said wheels for rotating the reel. 95
35. 6. In a reel, transporting means, reel supporting means comprising a plurality of wheeled axles in different horizontal planes, a rotatable reel, and means for supporting said reel on said axles in a position wherein the axis of one of said axles will be parallel to the axis of rotation of said reel and, extended, will lie within the cylindrical surface including the points in said reel most distant from the axis thereof. 100
40. 7. In a reel transporting means, a supporting frame provided on opposite sides of the longitudinal axis thereof with wheels of different diameters, a reel on said frame, and supporting means for said reel maintaining the same in a position wherein it is cut parallel to its axis by a plane including the axis of rotation of one of said wheels. 105
45. 8. In a reel transporting means, a supporting frame provided at one side of the longitudinal axis thereof with a pair of spaced supporting wheels, and on the other side of said axis with a larger supporting wheel, and a reel on said frame, said reel being supported for rotation in a position wherein the axis of said larger wheel is parallel to an element of the surface of said reel and spaced from the axis of said reel a distance less than the radius of said reel. 110
50. 9. In a reel transporting means, a supporting frame provided at one side of the longitudinal axis thereof with a pair of spaced supporting wheels, and on the other side of said axis with a larger supporting wheel, a reel on said frame, said reel being supported for rotation in a position wherein the axis of said larger wheel is parallel to an element of the surface of said reel and spaced from the axis of said reel a distance less than the radius of said reel, and driving means for said reel comprising an element coaxial with the axis of said larger wheel. 115
55. 10. In a reel transporting means, a plurality of wheel axles disposed in different planes, a reel supported thereby and intersecting the axis of one of said axles, and means for varying the effective length of the remaining axles. 120
60. 11. In a reel transporting means, a plurality of wheel axles disposed in different planes, a reel supported thereby and intersecting the axis of one of said axles, and means for permitting a telescopic movement of the remaining axles transversely beneath said reel. 125
65. 12. In a reel transporting means, a plurality of wheel axles disposed in different planes, wheels thereon, a reel above the axes of certain wheels intersecting the axis of another and driven therefrom, and means for adjusting the remaining wheels transversely of said reel. 130
70. 13. In combination, a truck, wheels therefor, a reel on said truck intersecting the axis of one of said wheels, a member disposed concentrically with said wheel and operatively connected to said reel, and a frictional connection between said member and said wheel. 135
75. 14. In combination, a truck, wheels therefor, a reel on said truck intersecting the axis of one of said wheels, a member disposed concentrically with said wheel and operatively connected to said reel, a frictional connection between said member and said wheel, and means for adjusting said connection from the exterior of said wheel. 140
80. 15. In combination, a truck, wheels therefor, a driving member disposed concentrically with the axis of one of said wheels, means including adjustable frictional means for connecting said member to said wheel, a driven member journaled on said truck and driven by said driving member, and a reel carried on said truck intersecting the axis 145

of said wheel and connected to said driven member.

16. In combination, a truck, wheels therefor, a rotatable gear disposed concentrically with the axis of one of said wheels, frictional means for connecting said gear to said wheel, a pinion journaled on said truck and driven by said gear, and a reel carried on said truck intersecting the axis of said wheel 10 and driven by said pinion.

17. In combination, a truck, wheels therefor, a driving member disposed concentrically with the axis of one of said wheels, means including adjustable frictional means 15 for connecting said member to said wheel, a driven member journaled on said truck and driven by said driving member, a reel carried on said truck intersecting the axis of said driving member and connected to 20 said driven member, and means for disconnecting said reel from said driven member.

18. In combination, a truck, wheels therefor, a rotatable gear disposed concentrically with the axis of one of said wheels, frictional means for connecting said gear to said 25 wheel, a pinion journaled on said truck and driven by said gear, a reel carried on said truck intersecting the axis of said rotatable gear and driven by said pinion, and 30 means for disconnecting said reel from said pinion.

19. In combination, a truck, wheels therefor, a rotatable gear disposed concentrically with the axis of one of said wheels, frictional means for connecting said gear to 35 said wheel, a pinion journaled on said truck and driven by said gear, a reel carried on said truck and driven by said pinion, and means on said reel and pinion for connecting 40 or disconnecting said reel and pinion upon a reciprocatory movement of said reel.

20. In combination, a truck having a plurality of axles disposed in parallel relation and projecting from one side thereof, wheels 45 carried on said axles, a larger wheel journaled on the opposite side of said truck from said wheels and disposed substantially midway between said axles, a reel carried on said truck above said axles, and means for 50 driving the same from said larger wheel.

21. In combination, a truck having a plurality of axles disposed in parallel relation and projecting from one side thereof, wheels 55 carried on said axles, a larger wheel journaled on the opposite side of said truck from said wheels and disposed substantially midway between said axles, a reel carried on said truck above said axles on an axis parallel to the axis of said larger wheel, and means for 60 driving said reel.

22. In combination, a truck having a plurality of axles disposed in parallel relation and projecting from one side thereof, wheels 65 carried on said axles, a larger wheel journaled on the opposite side of said truck from

said wheels and disposed substantially midway between said axles, a reel carried on said truck intersecting the axis of said larger wheel and extending below the latter to a point adjacent said axles, and means for 70 driving said reel.

23. In combination, a truck having a plurality of axles disposed in parallel relation and projecting from one side thereof, wheels carried on said axles, a wheel journaled on the opposite side of said truck from said wheels and disposed substantially midway between said axles, a reel carried on said truck above said axles, and means for driving 75 said reel from one of said wheels.

24. In combination, a truck having a plurality of axles disposed in parallel relation and projecting from one side thereof, wheels carried on said axles, means for adjusting 80 said axles transversely relative to said truck, a larger wheel journaled on the opposite side of said truck from said wheels and disposed substantially midway between said axles, a reel carried on said truck above said axles, and means for driving the same from said 85 larger wheel.

25. In combination, a truck, wheels therefor, a rotatable gear disposed concentrically with the axis of one of said wheels, frictional means for connecting said gear to said wheel, 90 a pinion journaled on said truck and driven by said gear, a reel carried on said truck and driven by said pinion, means on said reel and pinion for connecting or disconnecting said reel and pinion upon a reciprocatory movement of said reel, and means for locking said 95 reel in position.

26. In combination, a truck having a plurality of axles disposed in parallel relation and projecting from one side thereof, wheels carried on said axles, means for adjusting 100 said axles transversely relative to said truck, a larger wheel journaled on the opposite side of said truck from said wheels and disposed substantially midway between said axles, a reel carried on said truck above said axles, and means for driving the same from said 105 larger wheel including a slip clutch disposed within said wheel.

27. In combination, a truck, wheels therefor, a rotatable driving member disposed concentrically with the axis of one of said wheels, frictional means for connecting said member to said wheel, a driven member journaled on said truck and driven by said driving member, a reel carried on said truck intersecting the axis of said driving member and driven by said driven member, rotatable contact means on said reel, and cooperating 110 contact means non-rotatably attached to said truck for receiving current from the contact means on said reel.

28. In combination, a truck, wheels therefor, a rotatable driving member disposed concentrically with the axis of one of said 115

wheels, frictional means for connecting said member to said wheel, a driven member journaled on said truck and driven by said driving member, a reel carried on said truck and 5 operatively connected to said driven member, cooperating interlocking means between said driven member and the reel connectible upon a reciprocatory movement of said reel, and means for locking said reel against reciprocatory movement.

29. In combination, a truck, wheels therefor, a rotatable driving member disposed concentrically with the axis of one of said wheels, frictional means for connecting said member to said wheel, a driven member journaled on said truck and driven by said driving member, a reel carried on said truck and operatively connected to said driven member, cooperating interlocking means between 15 said driven member and the reel connectible upon a reciprocatory movement of said reel, and a rotary member interlocking with said truck and disposed concentrically with the axis of said reel for locking the latter 20 against reciprocatory movement.

30. In a reel transporting means, a plurality of wheel axles disposed in different planes, wheels thereon, a reel supported thereby and intersecting the axis of one of 30 said axles, driving means for said reel operatively connected to the wheel on said last mentioned axle, and means for varying the effective length of the remaining axles.

31. In a reel transporting means, a plurality of wheel axles disposed in different planes, wheels thereon, a reel supported thereby and intersecting the axis of one of said axles, driving means for said reel operatively connected to the wheel on said last 40 mentioned axle, and means for permitting a telescopic movement of the remaining axles transversely beneath said reel.

32. In a reel transporting means, a plurality of wheel axles disposed in different planes, wheels thereon, a reel above the axes of certain wheels intersecting the axis of another and driven therefrom, driving means for said reel operatively connected to the wheel on said last mentioned axle, and means 50 for adjusting the remaining wheels transversely of said reel.

33. In a reel transporting means, reel supporting means comprising a plurality of reel supporting wheels whose axes of rotation lie 55 in a plurality of horizontal planes, a reel rotatable about an axis spaced from said axes of wheel rotation, and means for supporting said reel on said wheels so that all points of the reel will rotate in planes intersecting a plane including two of said wheel axes.

34. In a reel transporting means, parallel wheeled reel supporting axles so disposed

that only a curved surface can include their axes, a reel, and means for supporting said reel whereby it is rotatable about an axis spaced from the axes of said axles and adapted to have all of its points rotate in planes intersecting a plane including a pair of said axes.

35. In a transporting means, wheeled reel supporting axles disposed in different horizontal planes, a reel rotatable about an axis spaced from the axes of said axles, means for supporting said reel so that all of its points 70 are rotatable in planes intersecting one of said planes, and means for rotating the reel.

36. In a reel transporting means, reel supporting means comprising a plurality of wheeled axles in different horizontal planes, 80 a rotatable reel drum having radially projecting flanges, and means for supporting said reel drum upon said axles in a position wherein the axis of one of said axles will be parallel to the axis of rotation of said reel 85 drum and, extended, will lie within the cylindrical periphery of the axially central part of said reel drum.

37. In a reel transporting means, reel supporting means comprising a plurality of 90 wheeled axles in different planes, a rotatable reel drum, and means for supporting said reel on said axles in a position wherein the axis of one of said axles will coincide with a line passing within the peripheral surface of 95 said drum and parallel to a generating element of such surface.

38. In a reel transporting means, a supporting frame provided on opposite sides of the longitudinal axis thereof with wheels 100 of different diameters, a reel on said frame, and supporting means for said reel maintaining the same in a position wherein it is cut, parallel to its axis, by a horizontal plane including the axis of rotation of the larger 105 of said wheels.

39. In a reel transporting means, reel supporting means comprising a plurality of reel supporting wheels whose axes of rotation lie 110 in a plurality of horizontal planes, a reel rotatable about an axis spaced from said axes of wheel rotation, and means for supporting said reel on said wheels so that a plane including two of said wheel axes will pass through the reel.

40. In a reel transporting means, parallel wheeled reel supporting axles so disposed that only a curved surface can include their axes, a reel, and means for supporting said reel whereby it is rotatable about an axis 120 spaced from the axes of said axles and is so disposed as to be cut by a plane including a pair of said axes.

In testimony whereof I affix my signature.

MORRIS P. HOLMES.
